Filed Dec. 4, 1963, Ser. No. 328,015
3 Claims. (Cl. 81—64)

This invention relates to a wrench, and specifically to a type of wrench employing a spiral spring for encircling and grasping the body of a cylindrical element.

This invention proposes the provision of a wrench capable of rotatably encircling an element to be removed, whereby rotation of the wrench in one direction increases its grip on the element, and rotation in the opposite direction decreases the grip. The wrench is constructed of a spirally-wound spring and a torque receiving and transmitting member attached directly to the spring on an arcuate portion of one of a plurality of turns comprising the spring, with the remainder of the turns being completely free to expand and contract at will, and to encircle the element for removal thereof.

The element to be removed by the wrench of the present invention is a conventional automotive oil filter, commonly called a spin-on filter. It is so called because all that is required to install the filter is to threadably engage a tapped opening formed on the longitudinal axis of the filter with an externally threaded stub shaft on a vehicle engine block. As the threading or rotating is readily accomplished, the filter can actually be caused to spin during the threading operation without a great deal of effort on the part of the mechanic.

Difficulty can ensue, however, with regard to removal of the filter, should the mechanic use an excessive amount of torque during the "spin-on" operation. Over a period of use, the threaded engagement can become sufficiently locked—so to speak—that reverse threading of the filter can not be accomplished by a normal application of torque thereto. The difficulty is enhanced due to the necessary provision on the filter of an O-ring which is compressed against the engine block as a result of installation of the filter. Due to the exposure of the ring to heat from the block and to heated oil, quite often the ring will swell, thus compounding the "locked" nature of the filter relative to the engine block.

When the filter is so locked, several makeshift means of removing the filter are resorted to by mechanics. Quite often a strap wrench will be used, but this use fails due to the surface of the filter being slick, having an oily film thereon. A mechanic might also punch a hole in the filter so as to force a bar therethrough to obtain leverage to rotate the filter. This latter method is quite unsatisfactory for several reasons. First, oil may spill from the filter thus making the operation rather messy. Secondly, the necessary room about the filter for accessibility of the bar may not be provided.

It is therefore an object of this invention to provide an improved wrench.

It is also an object of this invention to provide an improved wrench for rotatably removing a cylindrical element which has been rotatably engaged with an object.

It is another object of this invention to provide a wrench which encircles the element it is to rotate, and which wrench either increases or decreases its grip thereon depending upon its direction of rotation.

It is another object of this invention to provide a spiral spring torque wrench where the torque is applied to the spring at one end thereof on diametrically opposite points of a single turn, and further wherein a structure connected to the spring initially receives the applied torque on the longitudinal axis thereof.

It is an object of this invention to provide a wrench capable of accomplishing the above designated objectives

2

which is easily and economically manufactured, rugged in structure enabling repeated use thereof, and effective in operation.

These objects, and other features and advantages of this invention will become readily apparent upon reference to the following description, when taken in consideration with the accompanying drawings, wherein:

FIG. 1 is a perspective view of the wrench of this invention in assembled relationship with an automotive oil filter;

FIG. 2 is a side elevational view of the wrench of FIG. 1;

FIG. 3 is an end elevational view of the wrench, as viewed from the left end of FIG. 2;

FIG. 4 is a cross-sectional view taken along the line 4—4 of FIG. 3; and

FIG. 5 is a cross-sectional view taken along the line 5—5 in FIG. 3.

Referring now to the drawings, a preferred embodiment of the wrench of this invention is indicated generally at 10 in FIG. 1 and is shown in assembled relation with a conventional oil filter 11 which has been threaded onto the externally threaded stub shaft 12 protruding through an opening (not shown) in a vehicle engine block 13.

The filter 11 includes a circular, dome-shaped housing 14 which encompasses a filter screen 16, and which is closed at the bottom by a plate 17 having a plurality of arcuately spaced openings 18. Encompassing the openings 18 is an O-ring 19 which is bonded to the bottom of the plate 17. The plate is threaded internally at a thickened central portion 15 thereof for threading onto the stub shaft 12.

As discussed previously, due to a number of factors, at times the plate threads lock to the stub shaft 12 and the O-ring 19 sticks to the engine block 13 to an extent that an attempted manual turning of the filter 11 to thread it off the stub shaft can not be accomplished.

To overcome the locked nature of the filter 11, the wrench 10 is constructed so as to grip the surface of the filter housing 14 by means of a plurality of flat, steel bands as now described. The wrench 10 comprises in general a torque receiving element indicated generally at 20 in FIG. 2, and a member 21 connected to the torque receiving element adapted to completely encircle and grasp the filter housing 14 (FIG. 1). Upon receipt of torque by the element 20, the member 21 clamps the filter housing 14 with a pressure equally distributed over the full surface of the housing 14.

Specifically, the torque receiving element 20 includes an elongated U-shaped bar 22 having a flat central portion 23 (FIG. 4), a pair of flat side portions 24 extended oppositely each other downwardly and outwardly from the central portion 23 at equal angles, and a pair of flat ends 26 extended parallel each other and in planes at right angles to the plane of the central portion 23. As best illustrated in FIGS. 3 and 5, a pair of arms 27 extend in opposite directions from the longitudinal center of the bar 22 and at right angles to the main axis thereof. It will be noted (see FIG. 3) that the overall length of the arms 27 is less than the overall length of the central and side portions 23 and 24, respectively.

Secured to the bar 22 is a torque receiving hexagonal nut 28, a stem 29 of which is stationarily secured within a base 31 provided at the longitudinal center of the bar 21. In the specific embodiment of the wrench 10, the nut 28 may be rotated by any type of three-quarter inch wrench.

The member 21 comprises a spiral spring of spring steel having a plurality, approximately four, of turns 32, all of which are flat. A slight frustum is provided by each turn, 32a for example, nearest the bar 22 being slightly larger in diameter than the next succeeding turn

32. The end 33 of turn 32a is affixed by a pair of rivets 34 to the inner surface of one end 26, whereas a part of the turn 32a diametrically opposite the end 33 is also affixed by rivets 36 to the inner surface of the opposite end 26. The end 37 of the last turn 32b is turned inwardly toward the center of the spring member 21 as best seen in FIG. 3.

By referring specifically to FIGS. 2 and 3, it will be seen that the nut 28 is not only located at the longitudinal center of the bar 22, but it is also located on the longitudinal center of the spring member 21. Thus, torque is applied to the nut 28 and received by the bar 22 on the longitudinal center of the spiral spring 21. The torque applied to the torque receiving element 20 is then transmitted to the spring 21 to operate the wrench 10 in the following manner.

To install the wrench 10, the outer turn 32a at the open end thereof is placed over the outer end of the filter 10 and the wrench 10 is rotated in a clockwise direction as viewed in FIG. 1. This results in the spring part of the wrench 10 "walking" onto the filter 11 as the turns 32 tend to enlarge in diameter. The rotation is continued until the wrench completely encircles the filter to the fullest extent.

A wrench is then applied to the head nut 28, the wrench being of whatever type is permitted by the space available. The nut 28 is then rotated in a counter-clockwise direction. In response to this reversed rotation, the turns 32 tend to contract, resulting in their applying a pressure to the filter housing 14 over substantially its entire length and circumferentially a plurality of times depending on the number of turns 32.

Continued counter-clockwise rotation of the nut 28 transmits increased torque through the element 20 to the spring 21. It has been found that the provision of the arms 27, as illustrated prevents the bar 22 from absorbing undue tensile stresses and aids in transmitting a balanced and stabilized torque to the spring 21. This increased torque results in breaking the bond of the plate-to-stub shaft and/or the O-ring 19 with the engine block 13. The filter 11 is then completely rotated off the stub shaft 12. The wrench 10 can then be removed from the filter 11 by "walking" it off backwards—so to speak.

It can readily be appreciated that the installation of the wrench 10 and the removal of the filter 11 thereby are accomplished with ease and effectiveness which obviates punching holes in the filter and other messy and generally unsatisfactory makeshift filter removal devices.

Although a preferred embodiment has been described herein, it is to be remembered that various modifications

and alternate constructions can be incorporated therein without departing from the true spirit and scope of the invention as defined in the appended claims.

I claim:

5. A wrench for rotatably removing a circular element threadably attached to an object comprising in combination:

an elongated bar U-shaped in side elevation and having a pair of projections extended in opposite directions from the longitudinal center thereof, said bar adapted to receive torque; and

a resilient spiral member, said bar connected at opposite ends thereof to diametrically opposed parts of one end of said member.

10 2. A wrench for rotatably removing a circular element threadably attached to an object comprising in combination:

an elongated bar U-shaped in side elevation and having a pair of projections extended in opposite directions from the longitudinal center thereof;

a resilient spiral member, said bar connected at opposite ends thereof to diametrically opposed parts of one end of said member; and

a device secured to said bar at the longitudinal center thereof for receiving torque and for transmitting said torque to said bar.

15 3. A wrench for rotatably removing a circular element threadably attached to an object comprising in combination:

an elongated bar U-shaped in side elevation and having a pair of projections extended in opposite directions from the longitudinal center thereof;

a spiral spring, said bar connected at opposite ends thereof to diametrically opposed parts of one turn of said spring at one end thereof; and

a torque receiving and transmitting device secured to said bar at the longitudinal center thereof on the longitudinal center of said spring.
